Primary Examiner — Derrick E Holland*(74) Attorney, Agent, or Firm* — Haynes Beffel & Wolfeld LLP; Andrew L. Dunlap**(57) CLAIM**

The ornamental design for a solar panel clip, as shown and described.

DESCRIPTION

FIG. 1 is a top, right side, front perspective view of a solar panel clip showing my new design;

FIG. 2 is a rear elevation view thereof;

FIG. 3 is a top plan view thereof;

FIG. 4 is a right side elevation view thereof;

FIG. 5 is a left side elevation view thereof;

FIG. 6 is a bottom plan view thereof; and,

FIG. 7 is a front elevation view thereof.

The broken line portions of the solar panel clip form no part of the claimed design.
